SHUTTLE FOR LOOMS

Walter E. Burcham and George R. Hall, Elkin,
N. C.

Application April 7, 1939, Serial No. 266,656

1 Claim. (Cl. 139—196)

This invention relates to loom shuttles generally, and particularly to the type used in many weft-replenishing looms in which a feeler synchronized with the movement of the lay periodically enters a slot in the shuttle and touches the filling on the bobbin for the purpose of operating a weft-replenishing device when a certain extent of depletion of the weft on the bobbin is indicated by the extent to which the feeler has to move into the shuttle before being stopped by the bobbin.

In conventional shuttles of this type the thread emerging from the side eye passes along the body of the shuttle in a groove, the purpose of which is to keep the thread free and to prevent it from binding between the side of the shuttle and the adjacent side of the shuttle box. This groove generally intersects the feeler slot.

Not only is there risk of the thread slipping gravitationally beneath the groove and binding between the shuttle and shuttle box, but there is also the possibility that the feeler upon its incursion into the slot will catch the thread, either of which eventualities will break the thread.

The present invention has for its object the relocation of the thread groove in such a position that it cannot gravitate into the thin clearance space between the shuttle and the side of the shuttle box, and in such position that it does not intersect the feeler slot, so that it cannot possibly be caught by the feeler.

Other objects of the invention will appear as the following description of a preferred and practical embodiment thereof proceeds.

In the drawing which accompanies and forms a part of the following specification, and throughout the several figures, of which the same characters of reference denote identical parts:

Figure 1 is a perspective view of a shuttle embodying the principles of the present invention; and

Figure 2 is a cross-section of a shuttle and shuttle box taken in the plane of the feeler slot illustrating the coaction of the feeler and the bobbin.

Referring now in detail to the several figures, the numeral 1 represents the shuttle as a whole, comprising the wooden body 2, the metallic thread block 3, the side eye 4, and the recesses 5 open both at the top and bottom for the reception of the bobbin. The reference character 6 represents the feeler slot formed at the side of the shuttle body.

The shuttle, as above described, is of conventional form and in Figure 2 it is shown resting

in the conventional shuttle box 7, which has a slot 8 adapted to register with the slot 6 of the shuttle and through which aligned slots the feeler 9 extends into contactive relation with the filling 10 on the bobbin 11.

It will be understood from what has been said in the introductory part of this specification that the feeler enters the slot 6 of the shuttle vertically, and is stopped in its inward movement by the thread upon the bobbin. As the diameter of the weft on the bobbin decreases the feeler moves in farther at each incursion, and finally, when the thread on the bobbin is about depleted the feeler moves in so far that it actuates replenishing mechanism which pushes out 15 the empty bobbin and puts in a filled one.

The feeler and its mode of operation are conventional.

In known bobbins of this type a longitudinal thread groove is provided on the side of the bobbin 2, the purpose of which is to let the thread run out freely between the shuttle and shuttle box and not catch in the narrow clearance space 12 indicated in Figure 2. In known constructions the thread groove passes along the side of the shuttle in an intermediate plane which intersects the feeler slot 6. It is obvious that if for any reason the thread becomes slack it can fall to the bottom of this groove and become pinched in the narrow clearance space 12 below said groove. This will cause breakage of the thread. In known constructions the thread groove also intersects the slot 6 so that there is grave danger that the feeler 9 upon its inward movement will catch the thread and take it into the slot 6. This will also cause breakage of the thread.

By the present invention the structure of the conventional shuttle is modified so that the thread groove instead of being located at an intermediate longitudinal position along the side of the shuttle body is made in the form of a longitudinal rabbet 13 which obliterates the longitudinal bottom edge of the conventional shuttle and opens both on the side and bottom of the shuttle box as clearly shown in Figure 2, in which figure the thread in said rabbet is indicated by the reference character 14.

It is obvious that this thread cannot be caught in the thin clearance space between the sliding and guiding surfaces of the shuttle and shuttle box, for it can gravitate no lower than the bottom of the rabbet 13 which is of ample width to receive the thread freely.

Furthermore, the rabbet 13 avoids the feeler slot 6 entirely, so that it is impossible that the

thread shall be caught upon the feeler, dragged in by the feeler and broken.

In relocating the groove or rabbet 13 to the position described, it becomes necessary to guide the thread from the side eye into said groove, and this is accomplished by extending the horn 15 of the thread block, which flanks one edge of the side eye, to a lower than normal position, in which lengthened position it guides the thread accurately from the side eye into the rabbet 13.

It will be obvious to those skilled in the art that the thread groove of the present invention is not restricted to use with a shuttle of the type illustrated, but that it is useful with shuttles of any type in which there is risk of thread being pinched and broken between the shuttle and the

parts which it may engage in its course of travel.

What we claim is:

Loom shuttle having a thread block and side eye communicating therewith, a feeler slot in the same side as the side eye, said shuttle being provided with a thread groove formed as a longitudinal rabbet indenting the lower edge of the shuttle, spaced from the feeler slot and merging with said side eye, said thread block having a guiding horn at the side eye, extending down to said thread groove whereby the thread is directed into said rabbet and out of the path of the feeler slot. 5 10 15
